UNITED STATES PATENT OFFICE.

WARD H. SNYDER, OF CONGRESS PARK, ILLINOIS.

SPARK-PLUG.

1,352,554.

Specification of Letters Patent. Patented Sept. 14, 1920.

Application filed November 29, 1918. Serial No. 264,597.

To all whom it may concern:

Be it known that I, WARD H. SNYDER, a citizen of the United States, and a resident of Congress Park, county of Cook, and State of Illinois, have invented certain new and useful Improvements in Spark-Plugs, of which the following is a specification.

My present invention relates to improvements in spark plugs for internal combustion engines and has for its special objects, first, the provision of facilities for keeping the sparking terminals free from the deposition of carbon and the accumulation of lubricant which might by accumulation thereon interfere with the passing or sparking of the electric current; and, second, the provision of facilities for wiping or cleaning a portion of the insulating core of the spark plug and thereby preventing the accumulation of a carbon or oil deposit thereon which would interfere with the action of the plug, and, in the case of carbon deposit facilitate a leakage of the current and a diminution of the amount thereof which would otherwise be compelled to pass between the sparking terminals.

I attain the above objects by means of the structure and mechanism illustrated in the accompanying drawings, in which,—

30 Figure 1 is a central longitudinal section of a form of spark plug, embodying my invention;

35 Fig. 2 is a central longitudinal section of a slightly modified structure also embodying my invention.

Fig. 3 is an enlarged view of the lower end of one of the sparking terminals.

In the drawings, similar reference characters refer to similar parts throughout the 40 respective views.

The spark plug comprises an outer metallic shell the lower end 3 whereof is externally threaded to screw into the usual opening for the spark plug in an engine cylinder. The upper portion of the outer shell is enlarged at 4, and given a hexagonal or other suitable conformation so as to be easily engaged by a wrench. The outer shell is bored at 5 to receive an insulating core, the 45 upper portion of the bore at 6 being enlarged and interiorly threaded to receive a shoulder upon the insulating core and a retaining nut 7 to keep the insulating core in proper assembly with the outer shell. The insulating core 8 is provided with the exterior shoulder 9 to enter the large portion

of the bore 6 and to be retained in position by the nut 7. The insulating core is also centrally bored at 10 and in the lower end thereof, at 11, is provided a cylindrical recess. In the central bore 10 of the insulating core is mounted a metallic conducting rod 12, the lower end of which extends a suitable distance below the end of the core and is either headed or provided with a nut 60 at its lower end 13. Upon the upper end of the metallic rod 12 is provided a suitable binding nut 14 for the purpose of securing thereto a wire of the sparking circuit.

Mounted upon the lower projecting end 70 of the rod 12 is a piston head or disk 15 which is adapted to fit in the cylindrical recess 11 in the lower end of the insulating core. The piston head or disk 15 is provided with a downwardly extending tubular 75 neck 16 which preferably terminates in a disk-shaped lateral extension 17 which cooperates with the headed end or nut 13 upon the metallic rod 12 to prevent the removal thereof from the said rod. Depending from 80 the outer shell is a sparking terminal 18, the outer end of which is preferably looped upwardly and extended inwardly into the path of the disk-shaped extension 17. Upon the lower end of the sparking terminal 18 may 85 also be mounted a wheel or disk 19 to facilitate the passage thereby of the disk 17.

Behind the piston head or disk 15 and within the cylindrical recess 11 in the insulating core, is mounted a spring 20 of such 90 strength as to permit the compression stroke of the engine to drive the piston head or disk 15 sufficiently far into the recess 11 so as to position the disk-shaped extension 17 in proper sparking relation to the wheel or 95 inner end 19 of the sparking terminal 18.

It will now be seen that the movement of the disk-shaped extension 17 by the wheel 19 will detach from the respective parts any carbon deposition which may have occurred 100 on either of these parts; and it will also be seen that the movement of the piston head or disk 15 within the cylindrical recess 11 in the insulating core will also wipe the walls of the insulating core free from the deposition of carbon or other foreign matter.

In order that the end of the sparking terminal may not always strike the same spot upon the disk-shaped extension 17, I have provided means for causing a slight rotation of the latter, which means consist in providing a plurality of serrations or teeth

22 upon the upper surface of the headed end or nut 13 of rod 12 that coacts with a projection 23 upon the alining under-surface of disk-shaped extension 17, as shown in detail in Fig. 3. Owing to the helical form of the spring 20, the expanding thereof in returning the movable elements 15, 16 and 17 to their normal positions, will rotate it slightly at its lower end, thus causing a rotational movement of the disk-shaped extension 17. The projection 23 upon disk-shaped extension 17, in coaction with the serrations 22, will accentuate the rotational movement caused by the spring and thereby 10 present another surface of the disk-shaped extension 17 to the opposite sparking member.

15 In the modified construction shown in Fig. 2, the disk-shaped extension 17^a and piston head or disk 15^a and metallic rod 12^a, are or may be made integral, and the spring 20^a, instead of being installed within the cylindrical recess 11^a, behind the piston head or disk 15^a, is installed in a suitable cap 21 upon the top of the spark plug where the said spring will not be subject to as high heat as if installed within the cylindrical recess 11^a.

20 What I claim is:—

25 1. A spark plug for internal combustion engines comprising a metallic exteriorly threaded plug, a sparking terminal extending therefrom, an insulating core therefor having a cylindrical recess in its lower end, a central current conducting rod mounted within said core and extending below the same, a piston head movably mounted upon said current conducting rod and adapted to coöperate with the walls of said cylindrical 30 recess, a sparking point extended from said movably mounted piston head, and means for returning said movably mounted piston head to the outer portion of said cylindrical recess after the same has been forced therein by the compression developed in the cylinder of the engine.

35 2. A spark plug comprising a hollow metallic casing, a sparking point carried thereby, an insulating core mounted within said casing having a cylindrical recess in its lower end, a piston head mounted to reciprocate in said recess, a sparking member carried by said piston head, electrical connection with said disk and sparking member, and means for returning said piston head to its normal position after the same has been forced into said recess by pressure developed in the cylinder of the engine.

40 3. A spark plug comprising a hollow metallic casing, a sparking point carried thereby, an insulating core mounted within said casing having a cylindrical recess in its lower end, a current conducting rod disposed centrally in said insulating core and extending through and beyond said recess, a piston head movably mounted upon said rod within said recess, a sleeve depending from said piston head and surrounding said rod, and an annular extension on the lower extremity of said sleeve the movement of 45 which extension causes the same to engage said sparking point.

45 4. A spark plug comprising a hollow metallic casing, a sparking point carried thereby having a roller journaled in the outer end thereof, an insulating core mounted within said casing having a cylindrical recess in its lower end, a piston head mounted to reciprocate in said recess, a sparking member carried by said piston head, electrical connection with said disk and sparking member, and means for returning said piston head to its normal position after the same has been forced into said recess by pressure developed in the cylinder of the 50 engine.

55 5. A spark plug comprising a metallic casing, a sparking point carried thereby, an insulating core mounted within said casing having a cylindrical recess in its lower end, a terminal extended through said core and the recess therein, a sparking member carried by and movable on said terminal so as to engage and pass said sparking point, an extension on said member operable in said recess, and a spring in said recess between said extension and the inner end of said recess whereby said extension is normally positioned adjacent the outer end of said recess.

60 6. In a spark plug a casing provided with a sparking point, an insulating core mounted in said casing, a terminal rod carried by said core, a sparking member movable longitudinally upon said rod, and means for causing a rotation of said member upon said rod including a helical spring that normally retains said member adjacent the lower end of said rod.

65 Signed at Chicago, county of Cook and State of Illinois, this 20th day of November, 1918.

WARD H. SNYDER.
